RINGLIKE DEVICE

Filed June 14, 1937

Inventor:

Isidore Spinner,

By Louis Sheldon
Attorney.

UNITED STATES PATENT OFFICE

2,202,567

RINGLIKE DEVICE

Isidore Spinner, Chicago, Ill.

Application June 14, 1937, Serial No. 148,012

8 Claims. (Cl. 129—1)

This invention relates to books and more particularly to bindings, such for example, as those for holding together stacks of separate sheets of paper and the like.

An object of my invention is to provide a multi-piece binder ring whose pieces are completely separable and, when connected, and linked through a binding hole is capable of unlimited turning in the hole.

Another object is to provide binding means adapted to be supported by and capable of expeditious attachment to and removal from leaves or other material adapted to be bound thereby.

A further object is to provide a book assembly including a binder which binds a stack of sheets in such manner as to allow the top and bottom sheets to be flat, back to back.

A still further object is to provide binding means adapted to bear initials or other indicia.

Further objects and advantages of the invention will appear as the description proceeds.

Various forms of the invention are illustrated on the accompanying drawing, in which:

Fig. 1 is a fragmentary isometric view of a book assembly embodying my invention.

Fig. 2 is an elevation of a binder appearing in Fig. 1.

Figs. 3 and 4 are similar to Fig. 1 but show two other forms.

Fig. 5 is an enlarged isometric view of one of the binder elements.

Fig. 6 is similar view of the complementary binder element.

Fig. 7 shows how the split ring element is adapted to receive a stack of leaves.

Fig. 8 shows how the binder insert is movable through the binding hole in the stack of leaves.

Fig. 9 shows the elements incompletely assembled with the split ring element expanded from its dotted line shape.

Fig. 10 is a fragmentary sectional view through a binding hole of the stack of leaves held by the binder appearing in Figs. 1, 3 and 4.

Fig. 11 is a similar view but with the stack divided and lying on a desk or other support.

Fig. 12 shows a modified shape of insert end.

Fig. 13 shows a form of the invention similar to that of Fig. 9 but with the insert arched.

Fig. 14 shows a form similar to that of Fig. 13 but with the ends of the split ring of V-shaped cross section.

Figs. 15 and 16 show a reversal of the tongue-and-groove arrangement of Fig. 14, the insert being flat.

Fig. 17 is like Fig. 15 but with the insert arched.

Fig. 18 shows a form similar to that of Figs. 5 and 6 but with the ends of the split ring blunt.

Fig. 19 shows a form of interlock for the parts of the ringlike device.

Referring now more particularly to the drawing, it will be observed that a ring embodying my invention is of multi-part character and preferably consists of two pieces. In the illustrated examples one of the pieces is of more than 180° extent and the other is complementary thereto, 10 making a complete 360° ring. The pieces are preferably of the same width and of the same or approximately of the same thickness to resemble a one-piece ring and to be freely turnable without limit in a binding hole of the bound material. 15 The larger piece may be resiliently expandable to receive between the juxtaposed edges thereof the smaller piece or insert, and thereafter contracts itself to embrace the edges of the insert and thereby hold the insert in place. Preferably there 20 is a tongue-and-groove connection at the places of engagement of the pieces and they may be assembled and disassembled by being resiliently snapped together and apart, by frictional sliding, or in any other suitable manner. 25

In accordance with one form of my invention the ends or jaws 20 of the part-annulus 21 are of generally knife edge form as at 22, and the co-operating margins of the insert 24 complementally grooved as at 25 to snugly receive the edges 22. The insert 24 may be formed of flat strip as shown and, because of its small extent circumferentially relative to the complementary part 21, will not materially detract from the general circular appearance nor will it offer any interference 35 to passage of the full circumference of the ring through a binding hole in the bound material.

In Fig. 1 several rings 27 are linked through a like number of elongated marginal holes 28 in a stack of leaves 29, the holes being of sufficient 40 width to afford clearance for the free movement of the rings therethrough as shown in Fig. 10, while cooperating with the rings in holding the leaves with their edges substantially even, as when relatively rigid binding is employed. The 45 holes are accordingly preferably of substantially the same length marginally as the rings to allow free turning of the links while preventing unevenness of the edges of the leaves. The ring has the appearance in elevation seen in Fig. 2, 50 wherein the ends 31 of the insert are flush with the bases 32 of the member 21.

In Fig. 3, the binding rings 34 are relatively long, as are the binding holes 35 in the stack 36, and accordingly fewer are used. 55

In Fig. 4 the binding ring 38 and hole 39 in the stack 40 extend throughout substantially the full length of the binding margin.

- 5 5 Fig. 7 shows how a stack of leaves with one loading may be inserted between the ends 20 of any part-annular member of the invention, such, for example, as the member 21, with the binding hole arranged to receive either end 20. This figure also shows in dotted lines the member 21 10 linked through the hole.

10 Fig. 8 shows how with this construction one or more sheets 42 may be readily added and removed, the gap in the member 21 being afterward filled by the insert 24.

- 15 Fig. 9 shows in dotted lines at 16 the shape of the member 21 when unstressed and, in full lines, the shape when expanded to admit and resiliently clamp the insert 24 between the ends 20 of the member 21.

- 20 Fig. 10 shows how the pencil 44 appearing in dotted lines also in Fig. 1 may be clamped between the binding means and the stack.

As will be seen in Fig. 11, the book may be open and lie substantially flat.

- 25 Fig. 12 shows a modified insert 45 in which the groove at one or both ends may be rounded as at 46 to spread the ends of the insert 21 by a cam action to facilitate application of the insert.

- 30 In the form appearing in Fig. 13, the insert 48 differs from the insert 24 in that the insert 48 is concavo-convex in the direction of curvature of the member 21.

35 The form of Fig. 14 differs from that of Fig. 13 in that the insert 50 is of substantially the same thickness as the ringlike member 51 and the latter has its end edges V-shaped as at 52 from both sides to fit in complementary grooves 53 in the insert.

- 40 In Figs. 15 and 16 the flat insert 55 has its V-shaped edges 56 shaped to fit the V-grooves 57 in the ends of the ringlike member 58.

- 45 In Fig. 17 the construction is like that of Figs. 15 and 16 except that the insert 60 has the same curvature as the ringlike member 61.

- 50 Fig. 18 shows a structure similar to the first described form, differing therefrom only in that the end edges 63 of the ringlike member 64 cooperating with the insert 24 are not tapered.

55 Fig. 19 shows how any binder embodying my invention may be formed to insure proper alignment of its parts. The ringlike part 68 may have a notch 69 receiving a lug 70 on the insert 71, as also shown by way of example in Figs. 1, 2 and 12, although this construction may be reversed, as shown by way of example in Figs. 3 and 4, or otherwise modified.

60 Any of the various forms of inserts may bear indicia, as shown at 67 in Fig. 1. The complementary split ring elements may be left plain so that they may be linked with the material to be bound irrespective of the indicia-bearing inserts to be assembled therewith.

65 I am aware that many changes may be made and details of construction varied through a wide range without departing from the principles of my invention, and I therefore do not purpose limiting the patent granted hereon otherwise than as necessitated by the appended claims, which are to be interpreted as broadly as the 70 prior art will permit.

I claim:

- 75 1. A binder for a stack of leaves or the like, comprising a split resilient ringlike member having spaced jaws, an insert snugly and slidably engaged with and pinched by and between said

jaws, and means on said insert and one of said jaws for preventing insertion of said insert beyond a predetermined point in relation to said member, said member and insert having the same dimension lengthwise of the axis of said member and said means being disposed to be operative when said insert is fully inserted.

2. A ringlike device of the class described, comprising a split resilient ringlike member having spaced mutually facing end surfaces, an insert 10 terminating at and slidably engaged with and resiliently pinched by said surfaces, and means on said insert and one of said surfaces for resisting sliding of said insert along said surfaces beyond a predetermined point in relation to said member as said member and insert are assembled together to form the device.

3. A ringlike device comprising a split ringlike member having end edges substantially parallel to the axis of said member and spaced apart substantially less than the diameter of said member, a member shaped to correspond with the space between said edges and having complementary edges having a tongue-and-groove snug sliding fit with and longitudinally of the first mentioned 25 edges so as to be assembled with the first member by relative movement parallel to the axis of said first member, one of said members having a recess at an edge thereof, and a lug projecting from an edge of the other member and receivable in said recess to maintain said members in assembly.

4. A binder comprising a resiliently expandible and contractible split ringlike member having end edges substantially parallel to the axis of said member and spaced apart substantially less than the diameter of said member, a member shaped to correspond with the space between said edges and having complementary edges having a tongue-and-groove snug sliding fit with and longitudinally of the first mentioned edges so as to be assembled with the first member by relative movement parallel to the axis of said first member, one of said members having a recess at an edge thereof, and a lug projecting from an edge of the other member, the expansion of said first member admitting said lug to slide along the recessed edge and the subsequent contraction of said first member fitting said lug in said recess.

5. A binder comprising a resiliently expandible and contractible split ringlike member having spaced jaw edges, an insert terminating at and pinched by said edges and forming with said member a complete annulus capable of unlimited rotation through a binding hole in material to be bound, and means on said member and insert for preventing accidental disassembly thereof.

6. A binder comprising a split ringlike member having end edges substantially parallel to the axis of said member and spaced apart substantially less than the diameter of said member, a member shaped to correspond with the space between said edges and having complementary edges having a tongue-and-groove snug sliding fit with and longitudinally of the first mentioned edges 65 so as to be assembled with the first member by relative movement parallel to the axis of said first member, one of said members having a recess at an edge thereof, and a lug projecting from an edge of the other member and receivable in said recess to maintain said members in assembly, said ringlike member being resiliently expandible and contractible and pinching and forming with said insert a complete annulus capable of unlimited rotation through a binding 75

hole in material to be bound, said insert being formed for cooperation with said member with either face of said insert selectively disposed radially inward.

5. 7. A binder for a stack of leaves or the like, comprising a split ringlike member having spaced juxtaposed end faces, and an insert secured by and substantially entirely between said faces, said faces including means for preventing accidental 5
10 dis-assembly of said member and insert.

8. A binder for a stack of leaves or the like, comprising a split ringlike member having spaced juxtaposed end faces, and an insert secured by and substantially entirely between said faces, said faces including interlocking means formed to resiliently snap into inter-engagement when said member and insert are substantially completely assembled, to prevent accidental dis-assembly thereof.

ISIDORE SPINNER. 10

CERTIFICATE OF CORRECTION.

Patent No. 2,202,567.

May 28, 1940.

ISIDORE SPINNER.

It is hereby certified that error appears in the printed specification of the above numbered patent requiring correction as follows: Page 1, first column, line 10, for "provied" read --provide--; page 3, second column, line 2, claim 8, for the word "spit" read --split--; and that the said Letters Patent should be read with this correction therein that the same may conform to the record of the case in the Patent Office.

Signed and sealed this 23rd day of July, A. D. 1940.

Henry Van Arsdale,

(Seal)

Acting Commissioner of Patents.
